COMBINATION MILK BOTTLE AND PITCHER

Harvey Nagel, 22 17th St., Buffalo, N.Y.

Filed May 13, 1960, Ser. No. 60,565

Term of patent 14 years

(Cl. D58—6)

Fig. 2.

Fig. 3.

Fig. 1.

Fig. 4.

Fig. 7.

Fig. 5.

Fig. 6.

Fig. 1 is an elevational view of one side of a combination milk bottle and pitcher embodying my new design, the opposite side not shown being substantially the same in appearance.

Fig. 2 is a top plan view thereof.

Fig. 3 is an end elevational view taken from the left side of Fig. 1.

Fig. 4 is an end elevational view taken from the right side of Fig. 1.

Fig. 5 is a bottom plan view thereof.

Fig. 6 is a sectional fragmentary view taken on line 6-6, Fig. 1.

Fig. 7 is a sectional fragmentary view taken on line 7-7, Fig. 1.

I claim:

The ornamental design for a combination milk bottle and pitcher, substantially as shown and described.
